CLAIM

The ornamental design of a flexible PCB dual antenna module for use in smartphone, as shown and described.

DESCRIPTION

FIG. 1 is a perspective view of flexible PCB dual antenna module for use in smartphone representing first and second embodiments of the present invention;

FIG. 2 is a front view of the flexible PCB dual antenna module for use in smartphone of FIG. 1 according to the first and second embodiments;

FIG. 3 is a rear view of the flexible PCB dual antenna module for use in smartphone of FIG. 1 according to the first embodiment; and,

FIG. 4 is a rear view of the flexible PCB dual antenna module for use in smartphone of FIG. 1 according to the second embodiment.

The broken lines showing in the figures are for the purposes of illustrating and form no part of the claimed design.
